Emil Dischler, Au, Switzerland, assignor to Edwin
J. Schoettle Co., Philadelphia, Pa., a corporation of Pennsylvania

Application November 15, 1948, Serial No. 149,631

Term of patent 14 years

(Cl. D58—12.6)

To all whom it may concern:

Be it known that I, Emil Dischler, a citizen of the Republic of Switzerland, residing in Au, Canton St. Gallen, Switzerland, have invented a new, original, and ornamental Design for a Box, of which the following is a specification, reference being made to the accompanying drawing, forming a part thereof, in which:

Fig. 1 is a side elevational view of a box showing my new design;

Fig. 2 is a top plan view thereof;

Fig. 3 is a sectional view taken on the line 3—3 of Fig. 2; and

Fig. 4 is a perspective view thereof.

I claim:

The ornamental design for a box, substantially as shown.

EMIL DISCHLER.
